Kerr, Page, Cooper & Stayward, BY
his ATTORNEYS

UNITED STATES PATENT OFFICE.

ALBERT L. GALUSHA, OF SHARON, MASSACHUSETTS.

ATTACHMENT FOR GAS PRODUCERS.

1,409,941.

Specification of Letters Patent. Patented Mar. 21, 1922.

Application filed August 21, 1920. Serial No. 405,077.

To all whom it may concern:

Be it known that I, ALBERT L. GALUSHA, a citizen of the United States, residing at Sharon, in the county of Norfolk and State 5 of Massachusetts, have invented certain new and useful Improvements in Attachments for Gas Producers, of which the following is a full, clear, and exact description.

The invention which is the subject of my 10 present application for Letters Patent pertains to that class of apparatus known as gas producers, in which a gas for power or other purposes is obtained by passing, either by suction or pressure, a mixture of air and 15 steam through an incandescent bed of ignited fuel. My invention is an improvement in such apparatus, the primary purpose of which is to regulate the amount or quantity of such mixture so that it will always be in 20 substantially exact proportion to the amount of gas required and more especially so that the relative proportions of air and steam will remain the same regardless of 25 changes in the rate of gas production.

In this class of apparatus it is essential, 30 in order to obtain gas of uniform quality, that the relative proportions of steam and air remain always the same. In other words, if the apparatus be arranged or adjusted for delivering a given flow of gas, 35 conditions may be permanently established for supplying the proper amount of air and steam for producing such flow, but should twice as much gas be suddenly wanted, twice as much air and twice as much steam 40 should be immediately supplied to the producer. On the other hand, any less amount of gas being wanted the volume of air and steam actually delivered to the ash pit of the producer should be at once reduced in the same proportion.

Means heretofore devised or proposed for controlling the steam supply from a boiler for this purpose have proved unsatisfactory. 45 It may be effected by hand control of steam valves, but this is manifestly uncommercial and unsatisfactory, particularly when the demand for gas varies. On the other hand, when mechanical devices more or less automatic in their nature are employed for controlling the throttle valve it has been found that they cannot be wholly relied upon. Valves work harder at one time than at another. They frequently stick, while boiler 50 pressure is subject to variations, and all of these factors contribute to preventing the

obtaining of the desired result, the maintenance of the relative proportions of air and steam constant.

In order to avoid these difficulties I have 60 devised an apparatus which operates on a new principle and which is distinguished by the following characteristics:

First, the steam supply is maintained at 65 constant pressure.

Second, a constant uniform and unchanging flow of steam and air in the correct relative proportions and in volume sufficient to meet the maximum gas demand on the producer is provided for.

Third, a vent to the atmosphere is provided of such character that it takes care of all excess pressure, due to excess of air or steam and shunts such excess from the ash pit when the producer is lightly loaded.

I have found it possible to build an apparatus having these functions without those moving parts which, in previous devices, have proved so unreliable, and this apparatus is illustrated in the accompanying 80 drawing to which reference is now made for purposes of illustration. This drawing is a view mainly in vertical central section of the improvement shown applied to any proper form of gas producer.

The producer is indicated merely by the part 1, which may be the ash pit to which the regulator is attached. The latter comprises a dry steam pipe 2 from any suitable boiler or other source of steam, the pressure 90 of which may vary within reasonably wide limits, as, for example, from 90 lbs. to 130 lbs. In order, however, to secure a constant pressure a constant pressure reducing valve 3 is installed in this pipe, from which the 95 steam issues into the pipe 4, at, for instance, 14 lbs. constant pressure at all times.

The extension of pipe 4 contains a starting and stopping valve 6, which is wide open when the producer is operating and 100 closed tight when it is not in use, and a throttle valve 5 with fixed opening which, in connection with the constant pressure in pipe 4, gives a uniform and unvarying flow of steam at all times through the pipe 7. 105 The valve 5 is set to permit the maximum amount of steam to flow for the largest load the producer will carry during any given period.

The pipe 7 is extended in a vertical part 110 into a cylindrical chamber 8, where it is secured to a bracket or arm 9. It is threaded

and carries a valve plate 10, which is adjustable thereon to vary the passage for air down into the chamber 8, and is provided with check nuts 11 to secure the plate in adjusted position.

To the pipe 7, near its open end, is secured a bracket 12 carrying a conical valve 13, which may be adjusted to vary the orifice of said pipe. The closer this cone is brought to 10 the end of the pipe the more the stream of issuing steam is spread and the higher its velocity. This steam acts, therefore, to draw with it more or less air through the valve controlled top of the chamber and the relative proportions of steam to air are thus 15 regulated. The mixture of the steam and air is effected in the chamber 8, and passes from such chamber to the ash pit of the producer, whence it is caused to pass up through the 20 incandescent bed of fuel to produce the gas.

The horizontal chamber 14, which connects with the ash pit, has its opposite end provided with a balanced valve 15, and leads into a tube or chamber 16 open to the atmosphere, generally outside the building containing the producer. This valve is preferably hinged at 17, and carries adjustable weights 18 to which access may be had for 25 purposes of adjustment, by removing a cover 30 in the wall of the tube or chamber 16. The parts above described are all that are essential to the invention.

The operation of the device is manifest from the above description. When it is to be 35 used the pressure regulating and reducing valve 3 is set to yield the desired and constant pressure. The valve 5 is set to permit a flow of steam sufficient to take care of the largest demand for gas that will be required 40 during a given period. The clearance between the cone 13 and the end of pipe 7 is determined and the weights 18 are adjusted to give the desired air injection and the proper pressure at the outlet 21 into the ash 45 pit. The opening into the chamber 8 is also adjusted to give the correct proportion of air to the steam that is used.

These adjustments are made once for all. In operation the volume of mixed air and 50 steam passing to the ash pit is always in proportion to the gas taken off and used. If less gas is required the pressure in chamber 8 forces the excess of mixture out through the valve 15 to the atmosphere while an increased amount of gas takes more of this 55 mixture up from the ash pit.

In practice the valve 15 may be set to afford an exit of constant area, but when the producer is not in use it is desirable to close 60 this valve in order that air may not find its way to the bed of fuel and thus burning and wasting it.

This device constitutes a most efficient and

practicable means of control for gas producers. It has few parts, none of which 65 need be movable in the ordinary sense of that term. It is entirely automatic in its action and requires no close attention or change of adjustment.

What I claim as my invention is:

1. The combination with a gas producer, of a chamber through which a mixture of steam and air is admitted to the ash pit, and means for regulating the volume of such mixture flowing to the ash pit dependent for 75 operation on the pressure above that of the atmosphere in said chamber.

2. The combination with a gas producer of a chamber through which a mixture of steam and air is admitted to the ash pit, said chamber having two outlets, one for the passage of the mixture to the ash pit, and the other to the atmosphere, and an automatic valve controlling the last named outlet, operated by the pressure in the ash pit above 80 that of the atmosphere, whereby the volume of the mixture supplied to the ash pit is varied in accordance with the demand for gas.

3. The combination with a gas producer, of means for supplying steam thereto at a constant and uniform pressure, means for mixing with the steam a definite proportion of air and means for regulating the volume of the mixture entering the producer, by the pressure above that of the atmosphere at the 90 point where the said mixture enters the producer.

4. The combination with a gas producer, of means for varying the volume of admitted steam and air in accordance with the amount 100 of gas produced and used, comprising means for maintaining a constant pressure of the steam, means for mixing therewith a fixed proportion of air and means for shunting to the atmosphere all excess of mixture not required for the volume of gas produced.

5. The combination with a gas producer having a free relief opening to the atmosphere from the ash pit and means for preventing air from entering the ash pit 110 through said opening.

6. The combination with a gas producer, of means for supplying a mixture of steam and air at constant pressure and uniform 115 volume, means for regulating the proportion of such mixture which enters the producer dependent for operation on the pressure above that of the atmosphere at the ash pit, and means for varying or adjusting such pressure during the operation of the apparatus independent of the means for controlling the steam or air supply.

In testimony whereof I hereto affix my signature.

ALBERT L. GALUSHA.
